Primary Examiner—Nelson C. Holtje
Attorney, Agent, or Firm—St. Onge Steward Johnston & Reens LLC[57] **CLAIM**

We claim the ornamental design for a non-slip running-board, as shown and described.

DESCRIPTION

FIG. 1 is a side view of a non-slip running board mounted on a land vehicle;

FIG. 2 is a front perspective view of the non-slip running-board of FIG. 1;

FIG. 3 is a front elevational view of the non-slip running-board of FIG. 1;

FIG. 4 is a top plan view of the non-slip running-board of FIG. 1;

FIG. 5 is a right side elevational view of the non-slip running-board of FIG. 1;

FIG. 6 is a sectional view of Section 6—6 of the non-slip running-board of FIG. 4;

FIG. 7 is a sectional view of Section 7—7 of the non-slip running-board of FIG. 4;

FIG. 8 is a sectional view of Section 8—8 of the non-slip running-board of FIG. 4;

FIG. 9 is a top plan view of a second embodiment of a non-slip running board;

FIG. 10 is a top plan view of a third embodiment of a non-slip running board;

FIG. 11 is a right side elevational view of the non-slip running-board of FIG. 10; and,

FIG. 12 is a front elevational view of the non-slip running-board of FIG. 10.

The drawings show three designs which do not differ substantially from each other. FIGS. 1-8 show the first variant. FIG. 9 shows the second variant. FIGS. 10-12 show the third variant. The first variant has a lip (the left-side extension shown in FIG. 4) with three holes. The second variant has a lip with no holes. The third variant has no lip. The broken line showing of a typical land vehicle is for illustrative purposes only and forms no part of the claimed design.
